UNITED STATES PATENT OFFICE.

GEORGE DIEFENBACH AND HARRY WALDORF, OF GRANITE CITY, ILLINOIS.

PLATE-ROLLING-MILL ATTACHMENT.

1,135,996.

Specification of Letters Patent. Patented Apr. 20, 1915.

Application filed February 20, 1914. Serial No. 819,944.

To all whom it may concern:

Be it known that we, GEORGE DIEFENBACH and HARRY WALDORF, citizens of the United States, residing at Granite City, Illinois, have invented a certain new and useful Improvement in Plate-Rolling-Mill Attachments, of which the following is a full, clear, and exact description, such as will enable others skilled in the art to which it appertains to make and use the same, reference being had to the accompanying drawings, forming part of this specification, in which—

Figure 1 is a vertical section taken through the central portion of a plate rolling mill, and showing our improved scale removing attachment combined therewith. Fig. 2 is a rear elevational view of a rolling mill with our attachment applied thereto. Fig. 3 is a detail section taken approximately on the line 3—3 of Fig. 2, and showing one of the adjustable bearings for the rotary brushes forming a part of our improved rolling mill attachment. Fig. 4 is a view similar to Fig. 20 3, and showing the position of the adjustable brush bearing when the same has been moved to bring worn brushes into contact with the surface of the plate.

Our invention relates to a brush attachment for plate rolling mills, the principal object of our invention being to arrange brushes on the discharge side of a plate rolling mill, for the purpose of removing the scale from the surfaces of the rolled plates immediately after the latter pass from between the rolls.

In the manufacture of rolled metal plates, the billets from which the plates are rolled are heated prior to their passage through the rolling mill, and in heating, scale due to oxidation is formed on the surfaces of the billets and the proper time to remove this scale is immediately after the plate has been passed between the rolls the first time, or before it is re-rolled. It will be understood that each plate is passed several times between the rolls and the scale, if allowed to remain on the plate, is gradually pressed into the surface of the same, and if this scale is later removed accidentally or otherwise, it leaves a depression or thin place in the plate, thus making said plate defective. To overcome this objection we propose to arrange metal brushes adjacent to the rollers, and on the discharge side thereof, which

brushes are adapted to engage both upper and lower faces of the plate and remove the scale in the opposite direction to that in which the plate is traveling. Where rotary brushes are used the same are caused to 60 rotate in the opposite direction to that of the rollers of the mill so that the plate in emerging from between said rollers will contact with the brushes, so that the scale will be brushed off said plate in the direction opposite to that in which said plate is traveling. It is obvious that if the brushes are stationary the plate in passing between them will have the scale removed in the opposite direction to that in which the plate is traveling. 70

With the above and other objects in view, our invention consists in certain novel features of construction and arrangement of parts, hereinafter more fully described and 75 claimed.

Referring by numerals to the accompanying drawings, 10 designates the frame of the rolling mill, 11 the rolls thereof, 12 the table or support for the sheets as they are delivered to the rolls, 13 a transverse bar on the rear side of the mill, to which bar is attached a series of guide bars 14 which project toward the rolls and which support the sheets after the same have passed between the rolls. 85

Pivotedly mounted on the main frame of the mill and on the discharge side of the rolls is a pair of plates or bearings 15 in which are journaled the ends of rotary brushes forming a part of our improved attachment, said brushes comprising shafts 16 to which is applied in any suitable manner steel bristles. The upper one of these rotary brushes is arranged so that the ends of its bristles travel through a path which is directly above the upper edges of the guards 14 while the lower brush is arranged so that its bristles pass upward between the guard bars 14, and thus the upper and lower surfaces of the sheets passing over the guard bars are engaged by the ends of the bristles of both brushes. 95

Connected by ball and socket joints to the upper end of one of the bearing members 15 is the inner end of a screw rod 17, the same passing through an adjustable bearing 18 located on the frame of the mill, and the outer end of this screw rod is provided with a handle 19. By manipulating this screw rod the angularity of the bearing members 110

15 can be varied so as to change the position of the brushes and compensate for the wear upon the bristles thereof.

Where rotary brushes are utilized the 5 same are geared together by pinions 20 which are mounted on the shafts 16 near one of the bearing members 15 and said brushes are driven in any suitable manner, preferably by means of a motor driven 10 sprocket chain 21, which passes around a sprocket wheel 22, the same being fixed on the upper one of the shafts 16 near the end thereof.

The chain 21 is operated so as to drive 15 the brushes toward each other and toward the rolls 11, and as the plates emerge from between the rolls, their surfaces will be engaged by the ends of the steel bristles, and all scale will be removed from said plates.

20 As the ends of the steel bristles of the brushes wear off the screw rod 17 is manipulated to change the angularity of the members 15, and thus the brushes can be retained in service until the bristles are comparatively short. (See Fig. 4.)

25 An attachment of our improved construction is comparatively simple, can be advantageously used in connection with all forms of plate rolling mills and is very effective in 30 removing scale from the surfaces of the plates or sheets which pass through said mill.

It is obvious that various changes in the 35 size, form and construction of the various parts of our improved attachment may be made and substituted for those herein shown and described, without departing from the spirit of our invention, the scope of which is set forth in the appended claims.

40 We claim:

1. The combination with a plate rolling mill, of rotary brushes located on the discharge side of the rolls of said mill for engaging the plates or sheets discharged from 45 between said rolls, which brushes are geared to each other and driving means connected to one of said brushes.

2. The combination with a plate rolling mill, of rotary brushes arranged near the 50 discharge side of the mill adjacent to the rolls thereof for engaging the plates discharged from between said rolls, which brushes are geared together and are adapted to rotate in a direction opposite to that of the travel of the plate and driving means connected to one of said brushes.

3. The combination with a plate rolling mill, of rotary brushes arranged near the 60 discharge side of the mill adjacent to the rolls thereof for engaging the plates discharged from between said rolls, which brushes are adapted to rotate in a direction opposite to that of the travel of the plate, driving means connected to one of said 65 brushes and means for adjusting the angularity of said brushes with respect to the path of travel of the plates through the mill so as to compensate for the wear upon the bristles of said brushes.

4. The combination with a plate rolling 70 mill, of rotary brushes positioned adjacent the rolls of the mill on the discharge side thereof for engaging the plates emerging from between the rolls, and means directly connected to one of the brushes for driving 75 said brushes in the direction opposite to that of the travel of the plate from between the rolls.

5. The combination with a plate rolling 80 mill, of rotary brushes positioned adjacent 85 the rolls of the mill on the discharge side thereof for engaging the plates emerging from between the rolls, means directly connected to one of the brushes for driving said brushes in the direction opposite to that of the travel of the plate from between the rolls, and means for adjusting the angularity of the brushes with respect to the path of travel of the plates through the mill so as to compensate for the wear of the bristles 90 of said brushes.

6. The combination with a plate rolling 95 mill, of rotary brushes adjustably arranged on the discharge side of the mill for engaging the plates as they discharge from between the rolls, and which brushes are adapted to remove scale from the plate in the direction opposite to the travel of said plates.

7. The combination with a plate rolling 100 mill, of adjustable rotary brushes positioned on the discharge side of the mill adjacent to the rolls thereof and adapted to engage the upper and lower faces of the plates as they emerge from between the rolls and means 105 connected to said brushes whereby the same are positively and simultaneously rotated.

8. The combination with a plate rolling mill, of a pair of pivotally mounted bearings arranged on the discharge side of the 110 mill, rotary brushes journaled in said bearings, and means for driving said brushes toward each other and toward the rolls.

9. The combination with a plate rolling 115 mill, of a pair of pivotally mounted bearings arranged in the discharge side of the mill, rotary brushes journaled in said bearings, means for positively and simultaneously driving said brushes toward each other and toward the rolls, and means for adjusting 120 the angularity of the bearings.

10. The combination with a plate rolling mill, of rotary brushes arranged on the discharge side of the mill for engaging the plates as they emerge from between the rolls for the purpose of removing scale from said plates, means on the mill for positively and simultaneously rotating said brushes and means for adjusting said brushes to compensate for the wear of the bristles thereof.

11. The combination with a plate rolling mill, of adjustable rotary brushes located on the discharge side of the mill, means on said mill for positively and simultaneously driving said brushes and which brushes are adapted to engage the plates or sheets as they emerge from between the rolls of the mill.

In testimony whereof we hereunto affix our signatures in the presence of two witnesses, this 14th day of February, 1914.

GEORGE DIEFENBACH.
HARRY WALDORF.
